UNITED STATES PATENT OFFICE.

JOHN PURSEY GILBANKS, OF LITTLE NECK, NEW YORK.

DESIGN FOR A FLOWER BASKET.

Application filed April 19, 1924. Serial No. 9,316. Term of patent 3½ years.

To all whom it may concern:

Be it known that I, JOHN P. GILBANKS, a citizen of the United States, residing at Little Neck, county of Queens and State of New York, have invented a new, original, and ornamental design for a Flower Basket, of which the following is a specification, reference being had to the accompanying drawing, forming a part thereof, and in which:

Fig. 1 is a view in side elevation.

Fig. 2 is a plan view.

I claim:

The ornamental design for a flower basket, as shown.

JOHN PURSEY GILBANKS,
